US0D1097155S

(12) **United States Design Patent** (10) **Patent No.:** **US D1,097,155 S**
(45) **Date of Patent:** **** Oct. 7, 2025**

(54) **HANDLE FOR DENTAL INSTRUMENT**

(71) Applicant: **HU-FRIEDY MFG. CO., LLC**,
Chicago, IL (US)

(72) Inventors: **Erin Baumstark**, Chicago, IL (US);
James Stango, Chicago, IL (US)

(73) Assignee: **HU-FRIEDY MFG. CO., LLC**,
Chicago, IL (US)

(**) Term: **15 Years**

(21) Appl. No.: **29/918,894**

(22) Filed: **Nov. 30, 2023**

Related U.S. Application Data

(62) Division of application No. 29/845,195, filed on Jul. 5, 2022, now Pat. No. Des. 1,016,287, which is a division of application No. 29/739,798, filed on Jun. 29, 2020, now Pat. No. Des. 960,370.

(57) **CLAIM**

The ornamental design for a handle for dental instrument, as shown and described.

DESCRIPTION

FIG. 1 is an isometric view of a handle for dental instrument showing the new design;

FIG. 2 is a left side elevation view of the invention illustrated in FIG. 1;

FIG. 3 is a right side elevation view of the invention illustrated in FIG. 1;

FIG. 4 is a front elevation of the invention illustrated in FIG. 1;

FIG. 5 is a back elevation view of the invention illustrated in FIG. 1;

FIG. 6 is a top end plan view of the invention illustrated in FIG. 1; and,

FIG. 7 is a bottom end plan view of the invention illustrated in FIG. 1.

In the drawings, the equal-length broken lines depict portions of the handle for dental instrument that form no part of the claimed design.

1 Claim, 4 Drawing Sheets
